[57] CLAIM

The ornamental design for a removable module for an electronic peripheral, as shown and described.

DESCRIPTION

FIG. 1 is an enlarged top front and right side perspective view of a removable module for an electronic peripheral showing our new design;

FIG. 2 is a front elevational view thereof;

FIG. 3 is a top plan view thereof;

FIG. 4 is a right side elevational view thereof the left side being identical in appearance;

FIG. 5 is a bottom plan view thereof; and,

FIG. 6 is a rear elevational view thereof.

The circular pattern is partially shown in the views for ease of illustration and it being understood to continue across the entire surface where indicated.

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : **Des. 330,198**
DATED : **October 13, 1992**
INVENTOR(S) : **Robert Lajara, et al**

It is certified that error appears in the above-identified patent and that said Letters Patent is hereby corrected as shown below:

On the title page, Item [54]: Title should read;
--Removable Module For an Electronic Peripheral--.

Signed and Sealed this
Fifteenth Day of February, 1994
